LENS GRINDING AND POLISHING MACHINE

Lowell L. Houchin, Columbus, Ohio

Application April 13, 1936, Serial No. 74,065

4 Claims. (Cl. 51—160)

My invention relates to a lens grinding and polishing machine. It has to do, more particularly, with a machine for grinding and polishing lenses which is provided with a lens holder and a lap holder movable relative to each other; means being provided for simultaneously moving one of the elements both transversely and longitudinally relative to the other and additional means being provided for imparting a third movement so as to constantly change the path of movement and the extent of movement of one element relative to the other.

There have been a number of machines of the general type indicated above devised in the past. These machines usually embody a lap holder and a lens holder movable relative to each other. In order that the entire surface of the lens will be abraded by the lap, means is provided for moving one of the elements, usually the lens, relative to the other both transversely and longitudinally at the same time. However, in order to break up the lines of abrading and to reduce the chances of having inaccuracies in the finished lens, a third motion is usually employed. The third motion is accomplished by having additional means for moving the elements relative to each other so as to change the paths of travel of the movable elements during successive strokes and cycles of movement.

Although these prior art machines of the general type indicated have gone into extensive use, they are possessed of certain undesirable features. One of the greatest disadvantages of these prior art machines resides in the fact that they are of a complicated structure and, therefore, are expensive to construct and maintain. They are usually provided with a number of parts which do not wear for any appreciable length of time. Another great disadvantage of such prior art machines resides in the fact that they are so constructed that the third motion provided for breaking up the lines of grinding does not break up the lines sufficiently or as often as would be desirable. These prior art machines have been possessed of other undesirable features.

One of the objects of my invention is to provide a lens grinding and polishing machine which is provided with a lens holder and a lap holder, means being provided for simultaneously moving such elements relative to each other in two directions at right angles to each other, and additional means being provided for imparting a third movement to such elements so as to constantly change the path of movement and the extent of movement of one element relative to the other in order

to break up the lines of grinding to a greater extent and more often than with prior art machines and thereby obtain a more accurate surface on the lens.

Another object of my invention is to provide a machine of the type indicated which is of a very simple structure and is therefore inexpensive to construct and maintain and which is provided with a minimum number of parts which are subject to wear.

Another object of my invention is to provide a machine of the type indicated provided with means for bringing about three movements of the lens and lens-grinding lap relative to each other, such means being of such a nature that the three movements are independent of each other and, consequently, such movements may be controlled in such a manner that maximum breaking up of the lines of grinding will be obtained.

In its preferred form, my invention contemplates the provision of a machine embodying a base or housing having means for mounting a plurality of laps outside of the housing and on the forward wall thereof. Within the housing is disposed a frame or carriage which is adapted to carry a plurality of lens-holding members. These lens-holding members are so arranged that the lenses will contact with the surfaces of the laps which are disposed on the forward wall of the housing. The frame that carries the lens-holding members is so constructed that it may be rocked both longitudinally and transversely so that the lenses will simultaneously be reciprocated both longitudinally and transversely relative to the laps. I provide means for rocking the frame longitudinally and means for rocking it transversely, both of such means being adjustable to vary the extent of movement of the frame and, consequently, of the lenses relative to the laps.

I also provide additional means for obtaining a third movement of the lenses relative to the laps so as to break up the lines of grinding. This means preferably comprises mechanism for imparting an additional transverse movement to the frame in order to constantly change the extent of the transverse movement of the lenses relative to the laps. The machine is of such a type that the three movements are independent of each other and the speed of each movement may be selected so that maximum breaking up of the lines of grinding will be accomplished.

The preferred embodiment of my invention is illustrated in the accompanying drawings where-

in similar characters of reference designate corresponding parts and wherein:

Figure 1 is a perspective view of a complete machine made in accordance with the principles of my invention.

Figure 2 is a perspective view, partly broken away, showing the operating mechanism of my machine.

Figure 3 is a transverse section taken through the housing of the machine, certain portions of the machine being eliminated.

Figure 4 is a schematic figure of the machine, with the housing removed, illustrating the relative arrangement of the various operating parts of the machine.

Figure 5 is a section taken substantially along line 5-5 of Figure 4.

Figure 6 is a section taken substantially along line 6-6 of Figure 4.

Figure 7 is a diagrammatic illustration of the machine, showing the various movements and illustrating diagrammatically how the movements are brought about.

Figure 8 is a side elevation of a certain portion of the machine, illustrating mainly the two transverse movements of the frame of the machine and the means for bringing about such movements.

Figure 9 is a section taken substantially along line 9-9 of Figure 8.

Figure 10 is a view partly in perspective and partly in section illustrating the means which I have provided for clamping the lap in position.

Figure 11 is a perspective view of a lap which I preferably use on my machine.

Figure 12 is a diagram illustrating the path of movement of a point on the lens relative to the lens-grinding lap.

Figure 13 is a similar view illustrating the path of movement of a point on the lens relative to the lens-grinding lap after the machine has been adjusted to obtain a greater transverse movement than that illustrated in Figure 9.

With reference to the drawings and particularly to Figures 1 to 4, inclusive, my machine is shown as comprising a housing 1 which is preferably of substantially box-like form and is preferably made of metal. This housing preferably has a hinged door 2 at its top which is provided so that the operating mechanism of the machine may be reached for adjustment and other purposes.

Lens carrier

In the machine illustrated, I provide means for carrying two lenses although it will be apparent that the machine may be modified to carry a single lens or any number of lenses. I will first describe the means which I provide for carrying the lenses in order that they may be moved in two directions substantially at right angles to each other relative to the lens-grinding laps.

On the upper surface of the bottom of the housing 1 a bearing supporting member 3 is bolted. This bearing supporting member 3 has an upstanding bearing support 4 formed integral therewith at each end thereof. In each of the upstanding bearing supports 4 (Figure 9) a ball bearing 5 is disposed. A stub shaft 6 extends centrally through this ball bearing 5. On its inner end within the bearing support 4, the stub shaft 6 has an integral radially extending arm 7. This arm 7 has the outer reduced end 8 of a longitudinally extending shaft 9 keyed therein.

This shaft 9 extends from one bearing support 4 to the other, as indicated best in Figures 2 and 4. On the reduced portion 8 of the shaft 9 adjacent the arm 7 a roller bearing 10 is disposed. It will be noted that the shaft 6 is out of alignment with the portion 8 of shaft 9. Consequently, there is provided a pair of co-axially arranged eccentrics disposed at the opposite ends of the shaft 9 which I will designate generally by the reference character 11.

The frame for supporting the lens-carrying members is adapted to be mounted on the shaft 9 in such a manner that the eccentrics 11 will cause transverse movement thereof. This frame embodies a horizontally disposed lower portion 12 comprising transversely extending members 13 which are joined together by longitudinally extending members 14 and 15 which are integrally connected thereto. Substantially midway between the forward and rear ends of each of the transverse members 13 a bearing housing 16 is formed. These bearing housings 16 rotatably receive the roller bearings 10 of the eccentrics 11. It will be apparent that if the eccentrics 11 are rotated, the lower portion 12 of the frame 25 will be moved rearwardly and forwardly and also vertically. In other words, it will move through a rotary path in a vertical plane.

At each end of the lower portion 12 of the frame is an upstanding portion 17. This portion 17 of the frame is bifurcated at its lower end and straddles the transverse member 13 of the lower portion 12 of the frame. Each leg of the bifurcated lower end of the upstanding portion 17 of the frame is pivotally connected to the end of member 13 as at 17a. Each of the members 17 is thus so mounted on the lower portion 12 of the frame that it may be oscillated longitudinally of the frame and of the machine. I provide means for connecting the upper ends of the upstanding portions 17 so that they both simultaneously oscillate in the same direction. This means comprises a longitudinally extending member 18 which extends from one of the members 17 to the other. Adjacent each end of the member 18, it is provided with an upstanding portion 19. This upstanding portion 19 is disposed between the vertically extending arms of member 17 and is pivotally connected thereto as at 20. Thus, each end of member 18 is pivotally connected to one of the members 17.

The member 18 adjacent each end is provided with bearing housings 21 which are spaced laterally from the upstanding portion 19 which is disposed therebetween. These bearing housings 21 have ball bearings disposed therein which receive stub shafts extending from a yoke 22. Thus, the yoke 22 is free to rock in one direction on the member 18. An arm 23 having a pair of spaced depending portions 24 at its rear end is pivotally connected to the yoke 22 as at 25. Thus, the arm 23 may rock on the yoke 22 in a direction substantially at right angles to the rocking movement of the yoke 22 on the member 18. The arm 23 extends through an opening 26 in the forward wall of the housing. Thus, the arm 23 is free to rock both longitudinally and transversely of the machine on the frame which carries it. Also, the frame which carries it is free to rock both transversely and longitudinally of the machine. As previously stated, the rockable frame carries two of the arms 23, as indicated in the drawings, so that two lens holders may be provided on the machine.

The portion of each arm 23 that extends out

of the housing 1 is provided with a lens block carrying member 27. This member 27 may be of any suitable type but preferably embodies a member having a pair of depending pins 28 that project into sockets formed in the upper surface of a block 29 to which is cemented or otherwise secured a lens L. The pins 28 will permit reciprocation of the lens over the surface of the lap in both directions but will prevent rotation 10 of the lens relative to the lap. Consequently, this will insure that the curvature of the lap will be imparted to the surface of the lens.

At all the pivot points of the frame and at all the pivotal connections of the arms 23 to the frame I preferably provide roller bearings in order to eliminate friction and wear.

The lap holder

The means for holding the lap L' is indicated best in Figures 1, 3 and 10. As indicated in these figures, I provide means on the forward wall of the housing 1 for supporting a pair of lens-grinding laps L'. These laps are so disposed that the lenses carried by the arms 23 will be disposed directly thereabove. The two lap-supporting tables 30 are carried by a single support 31 which is bolted to the forward wall of the housing 1. The tables 30 project forwardly from the member 31. The upper surface of each of the tables 30 is substantially flat but has a depression 32 formed therein in order to produce an upstanding lug 33. The lug 33 projects above the surface of the table upon which the lap L' will rest as indicated best in Figure 3. The lower surface 35 of the lap is provided with a notch 34 (Figure 11). This notch is just slightly wider than the diameter of the lug 33 so that when the lug projects thereinto, the notch and lug will cooperate to prevent longitudinal movement of the lap 40 relative to the machine. However, because the notch is elongated, as indicated, transverse movement of the lap on the table will be permitted.

I provide means for clamping the lap in position in order to prevent the transverse movement. This means comprises a lug 35 with a straight forward edge arranged so that the rear edge of the lap will contact therewith and a clamping member 36 adapted to contact with the forward edge of the lap so that it will be firmly gripped between the clamping member 36 and the lug 35. The clamping member 36 is pivoted at its lower end as at 37 between a pair of lugs 38 on the lower and forward portion of the table 30. The upper end of the clamping member 36 has a rearwardly projecting finger 39 adapted to engage the forward edge of the lap L' as indicated in Figure 3. A screw 40 passes through the clamping member 36 intermediate its ends and is threaded into a bushing 41 disposed in an opening in the lap table 30. The screw is free to rotate in the opening in the member 36 through which it extends. The outer end of the screw is enlarged to form a handle portion 42, the inner end of which engages the clamping member 36.

It will be apparent that in using this clamping device, the lap L' is placed on the table with the notch 34 over the lug 33. Since the notch is of substantially the same width as the diameter of lug 33, longitudinal movement of the lap on the table will be precluded. The handle 42 of the screw may be turned until the finger 39 touches the forward edge of the lap L' and forces the lap transversely of the table into firm contact 75 with the lug 35. The lap will be tightly gripped

between finger 39 and lug 35. The notch 34 and the cooperating lug 33 serve to initially properly position the lap longitudinally of the table 30 and the clamping means serves to position it properly transversely of the table. 5

I provide means for effectively lubricating the screws 40 in order to prevent binding thereof. It will be apparent that the moisture from the abrasive, which is usually in the form of a paste, would tend to rust the screws 40. However, I 10 provide means for effectively lubricating the screws and thus eliminate any possibility of their rusting and binding.

This lubricating means comprises a reservoir 43 mounted on the member 31 intermediate the two lap tables 30. This member 43 has a cap 44 on its upper end which may be opened to permit filling with a lubricant. The lower end of the reservoir 43 is open and communicates with a vertical passageway 45 which in turn communicates with a horizontally extending passageway 46. The passageway 46 extends from the bore in which one of the screws 40 is disposed to the bore where the other screw is disposed. Thus, the lubricant is fed to the rear end of each of the screws 40. It will be noted that the screws are downwardly and forwardly inclined. Consequently, the lubricant will flow downwardly and forwardly along the entire length of the screws. Thus, the screws will be lubricated throughout 30 their length.

The depressions 32 in the lap tables will tend to collect any moisture which might seep beneath the laps and, therefore, will prevent sticking of the laps on the lap tables due to rust. The bottom of the housing 1 extends forwardly to form a shelf 1a which will catch any abrasive that falls off the laps. 35

Means for maintaining the lap and lens in contact 40

The means for maintaining the lap and the lens firmly but resiliently in contact with each other is indicated best in Figures 1 and 3. As illustrated, the forward portion of each arm 23 is downwardly turned as at 47 and then has a 45 forwardly extending portion 48. This portion 48 is at a level substantially corresponding with the level where the lens L and the lap L' contact with each other. This portion 48 has a cup 49 in its upper surface which receives a point 50 formed on the lower end of a rod 51. The rod 51 extends upwardly and has its upper end slidably mounted in a sleeve or collar 52 on the outer end of an arm 53. A compression spring 54 surrounds the rod 51 and the upper end of this spring abuts the portion 52 of arm 53 while the lower end of the spring bears against an enlargement 55 on the lower end of the rod. Thus, it will be apparent that the spring 54 will function to force the forward end of the arm 23, that carries the lens, 60 downwardly so that the lens will be in firm contact with the lap. 55

The arm 53 has a sleeve 56 on its rear end which loosely fits on an upstanding rod 57. A setscrew 58 is provided so that the arm may be adjusted vertically on the rod 57 and held in adjusted position. The lower end of the rod 57 is mounted in a member 59 which has a bifurcated lower end 60 which straddles a pair of lugs 62, projecting upwardly from the housing 1, to which it is pivotally connected by a pin 63. The member 59 has a slot 64 formed therein in which the rear end of an arm 65 is disposed. This arm 65 is pivotally connected to member 59 by a pin 66. The slot 64 is of such size as to permit lim- 75

ited movement of member 65 about pivot pin 66. The member 65 has a latch portion 67 adapted to cooperate with a keeper 68 immovably disposed between the lugs 62. The keeper has a lug 69 formed thereon. The forward end of arm 65 has a portion 70 formed thereon through which passes the upper end of a strap 71. The strap 71 is adjustably held in portion 70 by means of a set screw 72. The lower end of this strap 71 is connected to the forward end of arm 23 as at 73. The extreme forward end of arm 53 has a handle portion 74 formed thereon.

When the machine is not in use, as indicated in Figure 1, the arm 53 and rod 57 and associated parts are swung about the pivot pin 63 to cause the rod 57 to swing rearwardly and the forward end of arm 53 to swing upwardly. The latch portion 67 of arm 65 during such movement will drop behind the lug 69. Thus, the latch will function to keep the various parts in the position illustrated in Figure 1. During the described movement of arm 53 and rod 57, the forward end of arm 65 is also swung upwardly. Because of the strap 71, this will lift the forward end of arm 23 upwardly so that the lens L will be lifted out of contact with the lap L'. The lens may then be removed from the machine.

To adjust these parts again into operative position, it is merely necessary to move the arm 65 upwardly slightly to release portion 67 thereof from the lug 69. This will permit the rod 57 to swing forwardly and the arms 53 and 65 to swing downwardly. The arm 23 will also swing downwardly. The spring 54 will force the arm 23 downwardly so that the lens will be in firm contact with the lens-grinding lap. With the parts in this position, the latch portion 67 will be in front of the lug 69. Thus, these portions will normally tend to prevent upward swinging movement of arms 53 and 65. In other words, I provide means for locking the various parts in inoperative position as indicated in Figure 1 or in operative position indicated in Figure 3. The force of the spring 54 may be varied by adjustment of the arm 53 vertically on the rod 57. The fact that the point of application of the downward force by means of rod 51 and spring 54 is substantially at the level of the point of contact of the lens and the lap makes it possible to grind strong plus lenses on the machine. A downward pull will be exerted on the lens rather than downward thrust and this will make it possible to grind stronger plus lenses without danger of error.

55 Longitudinal movement

As previously stated, the frame which carries the arms 23, that carry the lenses, is free to rock longitudinally of the machine and such rocking movement will cause longitudinal movement of the lenses relative to the laps. The means for accomplishing this longitudinal movement is indicated best in Figures 2, 4 and 5. This means comprises a pitman 75 which has one end connected by a ball bearing pivotal connection to a depending bearing housing 76, on member 18 of the frame, as at 77. The opposite end of the pitman 75 is connected by means of an eccentric 78 to the forward end of a shaft 79. The eccentric 78 (Figure 5) comprises a disk 80 disposed eccentrically on the forward end of shaft 79 and formed integrally therewith. A disk-like member 81 is mounted on the member 80 and is free to rotate thereon being provided with a peripheral flange 81b that surrounds the member 80.

This member 81 has a pin 82, eccentrically disposed thereon which carries a ball bearing 81a to which the end of the pitman 75 is pivotally connected by means of a collar 75a on the pitman which surrounds the bearing. The disk 80 has a groove 83 on its periphery. Three members 84 project through the flange 82 of member 81 into the groove 83 in member 80. One of these members is an adjustable setscrew.

The shaft 79 and the pin 82 are out of alignment with each other. Consequently, when the shaft 79 is rotated, the frame will be rocked longitudinally of the machine by means of the eccentric 78 and the pitman 75. The extent of the longitudinal movement may be varied by adjusting members 80 and 81 relative to each other. To do this the setscrew 84 is loosened and then the member 81 is rotated relative to the member 80. This will vary the position of the shaft 79 and pin 82 relative to each other. Consequently, this will vary the lengthwise movement of the pitman 75. The pin 82 and shaft 79 are so arranged that they may be brought into alignment if desired. It will be apparent that if they are in alignment, there will be no lengthwise movement of pitman 75 and, consequently, no longitudinal rocking movement of the frame.

Transverse movement

As previously stated, the frame which carries the arms 23, that carry the lenses, is free to rock transversely of the machine and such rocking movement will cause transverse movement of the lenses relative to the laps. The means for accomplishing this transverse movement is indicated best in Figures 4, 6 and 8.

This means comprises a rocker arm 85 which is rigidly connected as at 86 to the member 15 of the lower portion 12 of the frame. This rocker arm 85 has its rear end pivotally connected as 40 at 87 to the lower end of a pitman 88. This pitman 88 has its upper end pivotally connected by means of a ball bearing 88a (Figure 6) to a pivot bolt 89 which has its head 89a disposed in a T-slot 90 extending across a disk 91 at the 45 center thereof. The bolt 89 may be adjusted to different positions along the T-slot 90 so that it will be located in different positions relative to the center of the disk 91. To facilitate description of the operation, I will designate this entire 50 eccentric structure by the reference character 92. The disk 91 is mounted concentrically on the end of a shaft 93 to which it is keyed.

It will be apparent that the shaft 93 and the disk 91 are rotated and if the pivot bolt 89 is disposed eccentrically on disk 91, the rear end of the rocker arm 85 will be swung upwardly and downwardly. This will cause swinging of the frame about the eccentric 92. Consequently, due to this transverse rocking movement of the 60 frame, the lenses will be caused to move transversely relative to the laps. The extent of the transverse movement will depend upon the position of the pivot bolt 89 relative to the center of the disk 91 and this may be varied whenever 65 desired.

Third movement

The means for accomplishing the third movement of the frame and, consequently, of the lenses relative to the laps has been previously described. 70 This means comprises the eccentric 92 which cause the frame to move in a rotary path transversely of the machine. The longitudinal movement, the transverse movement, and the third movement, which also might be said to be a 75

transverse movement, all occur simultaneously, as will be brought out more in detail hereinafter. The third movement accomplished by means of the eccentrics 11 will constantly vary the extent of the transverse movement produced by the eccentric 92. This is due to the fact that as the eccentric 92 causes the frame to rock about the eccentrics 11, the eccentrics 11 also rotate and cause the entire frame to move bodily forwardly and rearwardly. Thus, the extent of transverse movement produced by the eccentric 92 is constantly varied.

The driving means

15 The driving means is illustrated best in Figures 2, 3 and 4. For driving the various parts of the machine adapted to be driven, I provide an electric motor 94. This motor 94 is supported within the housing adjacent the rear wall thereof. The motor 94 may be controlled by means of a switch operated by a lever 95 which extends through a slot 96 in the side wall of the housing. The motor 94 is provided with a drive shaft 97. This shaft has a pulley 98 keyed on its outer 25 end. The pulley 98 drives a pulley 99, keyed on the outer end of one of the stub shafts 6, by means of a belt 100. The pulley 98 and the pulley 99 are of substantially the same size so that the two eccentrics 11 will be driven at substantially the same speed as the drive shaft of the motor. It will be apparent that both of the eccentrics 11 rotate together because they are connected by means of the shaft 9. The outer end of the drive shaft 97 projects through an opening 35 in the side wall of the housing and has a hand wheel 97a keyed thereon. This hand wheel 97a is provided so that the drive shaft 97 may be rotated manually when the motor 94 is not running. This may be desirable to properly adjust the machine before operation thereof is started.

The drive shaft 97 has a second pulley 101 keyed thereon which is smaller than the pulley 98. This pulley 101 drives a larger pulley 102 by means of a belt 103. The pulley 102 is keyed on the end of shaft 93 which drives the eccentric 92 provided for obtaining the transverse movement. It will be apparent that the eccentrics 11 will be driven faster than the eccentric 92. Consequently, the transverse movement accomplished by means of eccentric 92 will be slower than the third motion accomplished with the eccentrics 11. This results in the path of movement of the lens transversely of the lap, produced by eccentric 92, being changed several times, by means of eccentrics 11, during a single movement of the lens transversely of the lap from one edge thereof to the other. This insures that the lines of grinding will be broken up often and to a sufficient extent.

The drive shaft 97 of the motor also projects from the opposite side thereof. It drives a gear reduction unit 104. This gear reduction unit 104 is connected to the shaft 79 that drives the eccentric 78 which produces the longitudinal movement. The gear reduction unit is provided so that shaft 79 will be driven at a slower rate than the drive shaft. Thus, the longitudinal movement will also be at a slower rate than the third movement produced by the eccentrics 11.

The operation

In operation of the machine, the laps L' are first mounted on the lap tables in the manner described. The arms 23 are lowered into operative

position, the lens blocks 29 being placed beneath pins 28, where the spring 54 will exert a downward force, forcing the lenses firmly into contact with the laps. The latch 67 will be in front of lug 69 and will prevent accidental upward swinging of arms 53 and 65. The motor 94 may then be started by means of the switch lever 95. This will cause the driving mechanism to function.

The eccentric 78 will be driven and will cause reciprocation of the pitman 75. This will in turn cause longitudinal rocking movement of the frame which carries the arms 23. Consequently, the lenses on the forward ends of these arms will be reciprocated longitudinally of the laps. During this reciprocation, the arms 23 may pivot about pivot points 25 and, consequently, the surface of the lenses will always be in firm contact with the surface of the laps. Furthermore, the arms 23 will be free to swing in a vertical plane about the pivot points 21. This will permit the spring 54 to always hold the lenses in firm contact with the laps.

At the same time the eccentric 78 is driven, the eccentric 92 is also driven. This causes rocking of the rocker arm 85 and thereby produces transverse rocking movement of the frame which carries the arms 23. Consequently, the lenses are moved transversely of the laps. During this transverse rocking of the frame, the arms 23 will pivot about the pivot points 21 and the entire frame will pivot about the eccentrics 11.

Thus, it will be apparent that the lenses are moved relative to the laps simultaneously in two directions substantially at right angles to each other. However, simultaneously with such movements in both directions a third movement is produced by means of the eccentrics 11 which are driven comparatively fast. These eccentrics produce a back-and-forth and up-and-down, in other words, a rotary, movement of the frame. During this movement the arms 23 will pivot about the points 21. This causes a constant change in the path of movement since it varies the extent of the transverse movement produced by means of the eccentric 92. Since the eccentrics 11 are rotated at a greater rate of speed than the eccentric 92, the path of movement of the lenses transversely of the laps will be changed several times during a single movement of the lenses transversely of the laps from one edge thereof to the other. This will insure that the lines of grinding will be broken up sufficiently to overcome any chance of error.

The extent of the longitudinal movement may be varied by adjusting the eccentric 78 in the manner previously described. The extent of the transverse movement may be adjusted by adjusting the eccentric 92. In Figure 12 I illustrate the path of movement of a point on the lens relative to the lap, produced when the lens is mounted on my machine and the machine is operated. Figure 13 is a similar view illustrating the path of movement when the pivot bolt 89 of the eccentric 92 is adjusted farther away from the center in order to obtain a greater transverse movement.

One of the important features of my invention is that the three motions described are independent of each other. Thus, the speed of each movement may be different from the speed of the others.

It will be apparent from the above description that I have provided a machine having many desirable features. The machine is very simple yet very effective for the purposes for which it is in-

tended. Any of the pivot points or bearing points which might be subject to wear are provided with ball bearings. The machine is so constructed that the third movement provided therein is of such a nature that the lines of grinding are broken up to a greater extent and more often than with prior art machines.

Many other advantages will be apparent from the description and drawings and the following 10 claims.

Having thus described my invention, what I claim is:

1. A lens grinding and polishing machine comprising a lap holder and a lens holder, a frame 15 for carrying one of said holders, said frame being rockable both longitudinally and transversely of the machine so as to produce a longitudinal and transverse movement of the lens holder and lap holder relative to each other, means for rocking 20 the frame longitudinally of the machine, means for rocking the frame transversely of the machine, and means for bodily moving the frame in one of said directions to vary the movement of the lap and lens relative to each other, said last- 25 named means comprising an eccentric upon which the frame is supported and about which the frame rocks in the direction which it is moved by said eccentric.

2. A lens grinding and polishing machine comprising a lap holder and a lens holder, a frame 30 for carrying one of said holders, said frame being rockable both longitudinally and transversely of the machine so as to produce a longitudinal and transverse movement of the lens holder and lap holder relative to each other, means for rocking 35 the frame longitudinally of the machine, said means being manually adjustable to vary the extent of the longitudinal movement, means for rocking the frame transversely of the machine, 40 said last-named means being adjustable manu-

ally to vary the extent of the transverse movement, and means for bodily moving the frame transversely automatically during the transverse movement produced by said second named means in order to vary the extent of movement produced by said second named means, said last named means comprising an eccentric which supports said frame and about which the frame rocks transversely.

3. A lens grinding and polishing machine comprising a plurality of lap holders and a plurality of lens holders, means for supporting a plurality of the said holders of one type for movement relative to a corresponding number of holders of the other type, said means comprising a frame rockable both longitudinally and transversely of the machine so as to produce a longitudinal and transverse movement of the lens holders and lap holders relative to each other, means for rocking the frame longitudinally of the machine, 20 means for rocking the frame transversely of the machine, and means for bodily moving the frame in one direction to vary the movement of the holders relative to each other, said last-named means comprising a plurality of co-axially arranged eccentrics upon which the frame is supported and about which the frame rocks in the direction which it is moved by said eccentrics.

4. In a lens grinding and polishing machine a lap support, said lap support comprising a table 30 upon which the lap is adapted to rest, said table having a projection adapted to contact with one edge of the lap, a clamping member adapted to contact with the opposite edge of the lap, means for adjusting said clamping member comprising 35 a screw threaded into the lap support, said screw being disposed in inclined relation, and means for supplying lubricant to said screw at the higher end thereof.
